Primary Examiner — Ania Aman(57) **CLAIM**

The ornamental design for a fireplace as shown and described.

DESCRIPTION

FIG. 1.1 is a back view of a fire place;

FIG. 1.2 is a bottom view of the fire place;

FIG. 1.3 is a front view of the fire place;

FIG. 1.4 is a perspective view of the fire place;

FIG. 1.5 is a left view of the fire place;

FIG. 1.6 is a right view of the fire place; and

FIG. 1.7 is a top view of the fire place.

The broken lines shown in figures 1.2 and 1.4 are for the purpose of illustrating portions of the fireplace and forms no part of the claimed design.
